UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

DESIGN FOR A MAGNETO-CASING.

49,652.

Specification for Design. Patented Sept. 12, 1916.

Application filed May 10, 1915. Serial No. 27,277. Term of patent 14 years.

To all whom it may concern:

Be it known that I, CHARLES THOMAS MASON, a citizen of the United States, residing at Sumter, in the county of Sumter and State of South Carolina, have invented a new, original, and ornamental Design for Magneto-Casings, of which the following is a specification, reference being had to the accompanying drawing.

In the drawing wherein I have shown my new design Figure 1 is a side elevation, and

Fig. 2 is an end elevation looking from the right of Fig. 1.

I claim:

The ornamental design for a magneto casing as shown.

In testimony whereof I hereunto affix my signature in the presence of two witnesses.

CHARLES THOMAS MASON.

Witnesses:

H. R. VAN DEVENTER,
EDNA ISLER.
